(57) **CLAIM**

The ornamental design for a test meter, as shown and described.

DESCRIPTION

FIG. 1 is a front elevational view of the test meter;
FIG. 2 is a rear elevational view of the test meter;
FIG. 3 is a left elevational view of the test meter;
FIG. 4 is a right elevational view of the test meter;
FIG. 5 is a top plan view of the test meter;
FIG. 6 is a bottom plan view of the test meter;
FIG. 7 is a bottom frontal perspective view of the test meter;
FIG. 8 is a top rear perspective view of the test meter;
FIG. 9 is a left elevational view of the test meter in accordance
with an alternative embodiment;
FIG. 10 is a top plan view of the test meter; in accordance with
the alternative embodiment; and,
FIG. 11 is a bottom plan view of the test meter in accordance
with an alternative embodiment.

The front elevational view, the rear elevational view, the right
elevational view, the bottom frontal perspective view, and the
top rear perspective view of the test meter in accordance with
the alternative embodiment are identical to FIGS. 1, 2, 4, 7
and 8 respectively.

The long-short dashed lines represent the bounds of the claim,
and all other broken lines are for the purpose of illustrating
unclaimed portions of the test meter. None of the broken lines
form a part of the claimed design.
